(57) **CLAIM**

The ornamental design for a pump for liquids, as shown and described.

DESCRIPTION

The file of this patent contains at least one drawing executed in color. Copies of this patent with color drawings will be provided by the Office upon request and payment of the necessary fee.

FIG. 1 is a front top left perspective view of a pump for liquids showing a first embodiment of my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof;

FIG. 8 is a front top right perspective view of a pump for liquids showing a second embodiment of my new design, which includes line drawings corresponding to the first embodiment and in which color is not claimed;

FIG. 9 is a front elevational view thereof;

FIG. 10 is rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The other broken lines in the figures show portions of the pump for liquids that form no part of the claimed design.
